UNITED STATES PATENT OFFICE.

ALOYSIUS C. LIPPERT, OF KENOSHA, WISCONSIN, ASSIGNOR OF ONE-HALF TO C. A. NORTON, OF CHICAGO, ILLINOIS.

DESIGN FOR RADIATOR CAP FOR AUTOMOBILES.

Application filed January 24, 1923. Serial No. 4,977. Term of patent 3½ years.

To all whom it may concern:

Be it known that I, ALOYSIUS C. LIPPERT, a citizen of the United States, residing at Kenosha, county of Kenosha, and State of Wisconsin, have invented a new, original, and ornamental Design for Radiator Cap for Automobiles, of which the following is a specification, reference being had to the accompanying drawing, forming a part thereof.

On the drawing:

Figure 1 is a front elevation of a radiator cap in which my invention is embodied; and Fig. 2 is a side elevation thereof.

I claim:

The ornamental design for radiator cap for automobiles as shown.

ALOYSIUS C. LIPPERT.

Witness:

ETHEL WOOD.
